HUMIDIFYING AND COOLING APPARATUS

Raymond A. Robic, Outremont, near Montreal,
Quebec, Canada

Application October 27, 1937, Serial No. 171,330

5 Claims. (Cl. 261—92)

The present invention relates to improvements in humidifying and cooling apparatus.

An object of the invention is the provision of humidifying apparatus of generally improved 5 design.

Another object of the invention is the provision of apparatus which is highly efficient for humidifying and cooling atmospheric air for buildings, etc.

10 A further object of the invention is the provision of humidifying and cooling apparatus which is also highly efficient for cleaning and washing the air.

15 A still further object of the invention is the provision of humidifying and cooling apparatus having a rotor member designed to afford very efficient humidifying and refrigerative capacity.

Still another object of the invention is the provision of humidifying and cooling apparatus 20 which is constructed so as to present a large evaporation surface in a comparatively small compass.

25 Still another object of the invention is the provision of a humidifying and cooling apparatus having a rotor member which is durable, compact and relatively inexpensive in construction.

30 Other objects and advantages of the invention will become apparent as the description progresses.

In the accompanying drawings forming a part of this specification and in which like reference characters are employed to designate corresponding parts throughout the same:

35 Figure 1 is a front perspective view of the apparatus.

Figure 2 is a top plan view of the same.

Figure 3 is a vertical transverse section taken on the line 3—3 of Figure 2.

40 Figure 4 is a horizontal section through the apparatus.

Figure 5 is a vertical longitudinal section through the same.

45 Figure 6 is a fragmentary horizontal section of the clutch mechanism illustrating the gears engaged.

Figure 7 is a similar view showing the drive gear in disengaged position.

Figure 8 is a fragmentary vertical section of 50 the clutch mechanism.

Figure 9 is a fragmentary section through the rotor.

Figure 10 is a fragmentary section through the partly shaped rotor forming sheet.

55 Figure 11 is a top plan view of the same, and

Figure 12 is a fragmentary top plan view of the finally shaped sheet material.

Referring to the drawings, wherein for the purpose of illustration is shown a preferred embodiment of the invention, "B" designates the 5 casing of the apparatus, in the present instance constituting a cubical shell of sheet metal, wood or other suitable material. In the upper front portion is provided a rectangular elongated discharge opening 20, preferably covered with a 10 wire screen 21. A circular inlet aperture 22 is formed in the upper part of the rear wall. Thus, the bottom portion of the casing is constructed to provide a fluid-tight reservoir.

Upon the rigid tubular member 24 secured in 15 a transversely extending position in the casing is mounted a support frame embodying a sleeve 25 secured on the central portion of the tube. This frame is formed with a forwardly projecting arm 26 extending at an upward inclination 20 and provided at the front end with an annular bearing 27. From the rear of the sleeve 25 is extended an upturned support bracket 28 formed at the elevated rear end with a clamp bracket 29 slightly offset with respect to the axis of an adjacent horizontally extending bearing 30. The 25 frame is also preferably supported by a reinforcing rod 25' standing on the bottom of the casing and having the upper extremity fitted within a socket in the bottom of the frame. 30

The clamp 29 is adapted to firmly engage the stem 31 attached to and depending from the bottom of an electric motor 32 so as to support the motor with its shaft extending horizontally in the casing. At the rear end of the motor shaft 35 are mounted a plurality of radially extending fan forming blades 33 arranged within the inlet opening 22 in the rear of the casing. To the front end of the motor shaft is connected a worm 34 arranged to mesh with a complementary worm 40 wheel secured on the upper end of a shaft 35 journaled vertically in front of the motor. At its lower end, the shaft 35 is provided with a pinion 36.

The pinion 36 is adapted to mesh with a complementary bevel gear 38 slidably keyed on a horizontal drive shaft 39. The rear extremity of the shaft 39 is journaled in the bearing 30 while the forward portion is journaled in the bearing 27. A coil spring 40, mounted on the shaft 39 50 between a collar 41 fixed on the shaft and the front hub of the gear 38, tends to yieldingly retain this gear in engagement with the pinion 36. The gear 38 may, however, be selectively moved to disengage the pinion 36 by means of a dis- 55

engaging member 42 in the form of a yoke or loop slidable transversely relative to the shaft 39 between the rear hub of the gear 38 and the front face of the bearing 30. The elongated gear disengaging member 42 is formed so that one end portion 44 is of reduced width in comparison with a cam forming portion 45 at the opposite end. To the narrow end of the disengaging member 42 is connected a laterally extending operating rod 46 projecting through an aperture in a side wall of the casing and having an actuating knob 47 on the outer end. Thus, when the knob 47 is disposed in an inward position, as shown at Figure 8, the narrow portion 44 of the yoke 42 is disposed between the bearing 30 and the gear 38 and permits the spring 40 to retain the gear in engagement with the drive pinion 36. When the knob is pulled to an outward or extended position, as shown at Figure 7, the relatively wide cam portion of the yoke is slidably moved into position between the bearing 30 and the gear 38 so that the latter is slid forwardly on its shaft to disengage the drive pinion 36, providing a simple and effective clutch mechanism.

On the forwardly projecting end of the shaft 39 is mounted a rotor member R disposed so as to assume a position in the forward portion of the casing. This rotor embodies a centre member 50 in the form of a rigid disc having a hub 51 fitted on the shaft and secured thereto by a set screw 52. Upon the periphery of the centre disc is secured a concentric cylindrical ring 53 forming a core for the main section of the rotor or wheel. About this core is wound or coiled, in spiral formation, the fluid carrying section of the rotor consisting of a strip of flexible material 54 arranged to form a plurality of spaced convolutions. This coil is preferably formed of sheet metal of predetermined width, which is initially perforated, that is, is treated to form apertures 55 elongated longitudinally of the strip and arranged in transverse rows at spaced intervals, as shown at Figure 11. Prior to assembly, the strip 54 is subjected to an operation adapted to form folds or pleats 56 disposed transversely thereof on a line coinciding with the transverse centres of the apertures. This shaping of the sheet material provides transverse rows of folds projecting perpendicularly to a surface of the sheet and spaced transversely in correspondence with the width of the apertures 55. The folding operation is preferably effected so that the folds are normally approximately flat or closed, and may be resiliently expanded. As the strip is coiled about the rotor core, it is subjected to longitudinal tension so as to partially open the resilient folds, forming convolutions spaced in accordance with the length of the radially extending fold projections and resiliently retained in compact formation. A rigid ring 57, corresponding in width to that of the coil forming strip, is tightly fitted over and forms an exterior peripheral covering for the coil.

This construction provides a rotor in which the convolutions are spaced so as to form a structure designed to permit sufficient air passage, yet presenting a large evaporation surface within a comparatively small compass. Furthermore, the film of liquid carried by the rotor wheel functions to absorb matter such as dust and the like from the air, resulting in efficient cleaning and washing thereof. The form and arrangement of the projections on and the apertures in the rotor coil effects an agitation of the liquid which obviates accumulation of the solid particles re-

removed from the air upon the wheel, with the result that such matter settles at the bottom of the liquid reservoir. This sediment may be readily removed from the reservoir by draining and cleaning the same about once a year or as the particular circumstances may require.

As illustrated at Figures 3 and 5, a flaring transversely curved hood 58 is mounted in the upper rear portion of the casing to effectively direct the air current from the fan through the 10 upper portion of the rotor. A pair of complementary deflector members 59 are mounted on the support tube 24 at each side of the frame structure. Each of these deflectors embodies a transversely extending plate section secured on 15 the tubular support by screws or like fastening elements and mounted to assume an inclination so that the front edge is higher than the rear edge, as shown to advantage at Figure 5. At the inner end of the inclined plate, each of the deflectors is formed with an upwardly extending side plate turned in horizontal inclination so that the two vertical deflector plates diverge toward the front of the casing. This deflector construction is designed so as to deflect the air current 20 from the fan upwardly and laterally into the side liquid carrying portions of the rotor coil.

A tube 60, adapted for connection with a source of fluid supply, extends through the rear wall of the casing and connects with an automatic control valve 62, supported within the casing by an angle bracket 63. The automatic valve 62, which may be of any known construction, preferably embodies an operating lever 64 having a float 65 attached to the free end so that the fluid in the reservoir of the casing will be automatically maintained at a predetermined level. A pipe 67, providing an overflow drain, may also be connected with the rear wall structure. Electric conductors 68, for detachably connecting the motor 32 with a source of electric current, may also advantageously extend through the upper portion of the rear casing wall, as shown at Figures 3 and 4.

During operation of the apparatus as an air humidifying and cooling medium a fluid, such as water, is conducted into the reservoir and maintained therein at a suitable level, preferably at a level sufficient to cover the bottom portion of the coil of the rotor. The motor 32 is then put in operation so as to effect rotation of the blower fan and the rotor. The current of air passing through the open-ended casing by the action of the blower is forced through the upper part of the rotor coil which carries a film of water, effecting evaporation of the liquid and liberating moisture into the air stream so that the atmospheric air of a room or building may be humidified and cooled to a selected degree. As is well known, the evaporation of the water causes dissipation of heat energy and consequently effects a lowering of the temperature of the rotor coil. As a result thereof and the particular structure of the coil, the rotor presents a relatively large cooling area of low temperature compared to normal room temperature so as to efficiently cool the current of air blown through the coil by the action of the fan.

As will be apparent from the description thereof, the rotor is so constructed as to provide a comparatively light and durable, yet relatively inexpensive fluid exposing member which is most efficient for the required operation. By reason of the resilient assembly thereof, the coil section

will permanently retain a compact condition yieldingly conformable to variations caused by expansion and contraction without loosening so as to enable operation with a minimum of annoying sound. The arrangement of the folded resilient projections of the coil also serves to retain the convolutions at suitably spaced positions, while the provision of the apertures therein will allow proper drainage of the coil and avoid the carriage of excess liquid into the air stream. Inasmuch as the evaporation of the liquid on the rotor produces a substantial reduction in temperature, as for instance about 11°, it will be apparent that the apparatus presents a machine which is highly efficient as a refrigerative or cooling medium for summer operation, in addition to its utility as a humidifying apparatus.

The clutch mechanism associated with the drive gear enables selective disconnection of the rotor from the motor so that the fan may be employed as a cooling and air circulating medium independently of the humidifying wheel.

It is to be understood that the form of my invention herein shown and described is to be taken as a preferred example of the same, and that various changes as to the shape, size and arrangement of parts may be resorted to without departing from the spirit of the invention or the scope of the subjoined claims.

Having thus described my invention, I claim:

1. A humidifying and cooling apparatus comprising a casing adapted to provide a fluid reservoir in the bottom portion thereof, the said reservoir having inlet and outlet openings in the upper rear and front portions, a support member supported transversely in the casing, a sleeve secured on the intermediate portion of the support member, an arm extending forwardly from the sleeve having a bearing element thereon, a bracket extending rearwardly from the sleeve formed with a shaft bearing, a longitudinally extending shaft journaled in the said bearings, a motor mounted on the bracket, a blower fan in the rear portion of the casing operatively connected with the motor, speed reduction gearing between the drive shaft of the motor and the longitudinal shaft, a rotor core secured on the longitudinal shaft, a spiral coil of sheet material wound about the core having resilient folded pro-

jections spacing the convolutions of the coil, and a ring secured about the periphery of the coil.

2. In a humidifying apparatus including an open-ended casing providing a reservoir in the bottom portion, a drive shaft rotatably supported in the casing, a blower operable to force a current of air through the upper portion of the casing, means for rotatably operating the drive shaft and the blower, a rotor secured on the shaft so that its bottom portion will extend within the reservoir, the said rotor including a coil of sheet metal wound in spiral formation and formed by initially perforating the sheet metal and forming folds transversely of the perforations to provide a plurality of transversely and longitudinally spaced folds projecting perpendicularly from the sheet and winding the said sheet material under tension to form a compact resiliently yieldable coil, and a rigid ring fitted tightly about the periphery of the coil.

3. In a humidifying apparatus, a rotor-coil including a strip of sheet material wound in spiral form, the said strip being shaped to provide transverse rows of spaced apertures and resilient radially projecting folds bent on a transverse line separated by the apertures so that the coil may be wound under spring tension.

4. In a humidifying apparatus, a rotor core, a strip of sheet material wound in spiral form about the said core, the said strip having transverse rows of apertures formed therein at spaced intervals and having resilient radial folds bent on a transverse line through the apertures, and a rigid ring fitted tightly about the periphery of the spiral strip.

5. In a humidifying apparatus, a casing having a reservoir in the bottom and openings in the upper parts of the front and rear walls, a rotor shaft supported horizontally in the casing, a motor mounted in the casing and having connection with the shaft for rotating the same, a core secured on the shaft, and a strip of sheet material wound in spiral form about the core, the said strip being provided with apertures arranged in transverse rows and having resilient radially projecting folds bent on a transverse line through the rows of apertures, so that the strip may be wound under spring tension.

RAYMOND A. ROBIC.
